UNITED STATES PATENT OFFICE.

EDWARD F. CHANDLER, OF BROOKLYN, NEW YORK, ASSIGNOR TO CHANDLER DEVELOPMENT CORPORATION, A CORPORATION OF NEW YORK.

TORPEDO-BOAT.

1,266,103.

Specification of Letters Patent. Patented May 14, 1918.

Application filed December 9, 1915. Serial No. 65,977.

To all whom it may concern:

Be it known that I, EDWARD F. CHANDLER, a citizen of the United States, residing in the borough of Brooklyn, county of Kings, 5 city and State of New York, have invented certain new and useful Improvements in Torpedo-Boats, of which the following is a full, clear, and exact description, reference being had to the accompanying drawings, 10 forming a part of this specification.

This invention pertains to torpedo vessels and the launching of torpedoes from torpedo carrying vessels. The apparatus embodying my inventive idea and the method 15 of operation set forth greatly facilitate accurate torpedo shooting from torpedoplanes, motor-boats, submarines and all types of craft.

As is well known the usual torpedo craft is 20 about 200 ft. long and has a beam of about 25 or 30 ft. and although this is considered a comparatively small vessel, it is nevertheless several times larger than my vessel in its preferred form. Torpedoes generally are 25 shot from a launching tube and owing to the characteristics of the present standard type of torpedo steering control comparative stability of the vessel upon which the torpedo guns are mounted is an important factor. 30 Although some of the submarines from which torpedoes are launched with comparative accuracy, are somewhat less than 200 ft. in length it is a fact that comparative stability exists in such a vessel only 35 when it is fully submerged and not affected by the action of the water and it is in this submerged state that torpedoes are usually launched.

Now it is my purpose to produce a small 40 sub-surface vessel; in other words a vessel adapted to expose only a small part of its hull above the waterline.

Furthermore, it is my object to provide 45 means by which such a vessel although greatly affected by the action of the water, waves, etc., is still adapted to efficiently handle its torpedoes, and I accomplish my purpose first by providing a vessel of novel design, and secondly by providing means 50 whereby the gyroscope of the torpedo carried by my vessel may be started spinning in advance and released when the torpedo is launched or disengaged from the carrying vessel.

55 Another object of my invention is to pro-

vide a vessel adapted to carry externally two comparatively large torpedoes which may be launched singly or together and which do not depend upon the directing influence of a launching tube for their accuracy in direction.

Further objects will be brought out and others will become apparent as the following specification and description is read in conjunction with the drawings herewith, in which—

Figure 1 is a side elevation illustrating diagrammatically the general scheme of my vessel;

Fig. 2 is a schematic plan view adapted better to show the position of the two torpedoes;

Fig. 3 is a conventional bow elevation;

Fig. 4 illustrates a method of hanging the torpedo from the hull of the vessel.

Fig. 5 is another detail view of the same.

Fig. 6 illustrates diagrammatically the apparatus for starting the torpedo mechanism.

Fig. 7 illustrates diagrammatically the end elevation of a part of the former.

Fig. 8 illustrates schematically the torpedo mechanism and the apparatus for controlling the same.

Fig. 9 is a modification of Fig. 3.

Fig. 10 is a diagram of the starting latch and gyro spinning mechanism.

Referring to Fig. 1, it will be noted that I provide for the employment of a vessel 1 of any suitable form adapted for the purpose, with which is associated means 2 for carrying externally a torpedo 3. 4 is a member operated from inside the boat and adapted to trip the starting latch 5 of the torpedo for the purpose of launching the same upon its course. 6 is a propeller of my vessel which is operated by any suitable motive power adapted to be carried within said vessel, and 7 is the steering rudder. 8 is a conning tower. 10 is a mast which if employed is adapted to support a radio aerial 11, it being understood that it may be desirable to either equip the vessel for radio communication such as telegraphy or teletphony, or for the purpose of receiving or sending radiant energy for some or any purpose. 12 is a ventilator which may be of any suitable form and which is adapted either to furnish air to the interior of the boat or to permit air or gases to be expelled. 13 represents a gun of any suitable pattern and

which, incidentally, may be located in any suitable part of the vessel.

In Fig. 2 it will be noted that deck details have been eliminated, the purpose of this view being to show in a general way the position of torpedoes 3 and 3' which, as shown, are preferably forward of amidships though not extending beyond the bow of the vessel. The exact position of the torpedoes, however, is optional except that as shown in Fig. 3 I prefer that they should be below the bulk of the hull of the vessel and hung upon suitable members 2 and 2'. 14 and 14' represent ribs or fins which may be carried by the hull 1 for the purpose of protecting the torpedoes against collision, etc.

In Fig. 4, 2 is a suitable lug or bracket secured to the hull of the vessel, and 15 is a suitable eye member secured to the torpedo body and 16 is a pin or bolt adapted to pass through 2 and 15 for the purpose of maintaining them together, substantially as shown.

In Fig. 5, 2 is the part attached to the hull of the vessel, 1 being a part of the shell of the hull. 15 is the lug member secured to the torpedo 3 and 16 is the pin or bolt which when in a position substantially as shown acts to hold the torpedo in place. Secured to the inside of the hull 1' is a bracket 17 upon which is hung a bell crank 18 adapted to turn about a pivot 19. At the upper end of the bell crank I have shown for convenience a foot plate 20 and have illustrated the lower end of the bell crank as connected with pins 16 and 21, the said pin passing through the hull at 22. By this arrangement it will be seen that by pressing down upon 20, pin 16 will be removed from the torpedo lug thus freeing the weapon without the necessity of the same moving forward as is required when a tube or slide-way is employed. Obviously the torpedo when released will fall away from the hanging means and as there is no guiding means the torpedo will be released instantaneously. It will be seen that this method of hanging and releasing a torpedo is well adapted for employment where the speed of the boat is the same or in excess of the speed of the torpedo itself. Where a torpedo tube or other direction maintaining means such as a slideway is employed, relative longitudinal movement between the torpedo and the boat is necessary to effect the release.

In Fig. 6, 3 is the torpedo and 1 is the hull of the vessel most of which has been broken away and 4 is a lever located upon the outside of the vessel, 5 is the starting latch common to all torpedoes. Passing through the wall of the hull is a shaft 23, to the outer end of which is securely fastened lever 4 and to the inner end lever 24 is securely fastened. 25 is a treadle or lever 65 secured to a part of the hull in any conven-

ient manner and at any desirable point and adapted to swing about a pivot 26. Connecting lever 25 with 24 is a connecting rod 27. Secured to the under side of the hull is a slotted member 28 more clearly shown in Fig. 7. Upon the torpedo is located and securely carried thereby a T-shaped member 29 by means of which the torpedo is carried by 28. When lever 25 is moved to the right motion will be transmitted to lever 4 which will throw the starting latch 5 back or to the left. This will start the propelling mechanism of the torpedo which in turn will cause the torpedo to disengage itself from the slide member 28, as will be readily understood. The employment of a comparatively short slide member substantially as shown obviates to a very large degree the danger of the weapon fouling during its launching when operating in a heavy sea.

In Fig. 8, 28 is the slide member carried by the hull and 29 is the T-shaped member carried by the torpedo and by means of which the torpedo is held in engagement with the hull. 4 is a lever located upon the outside of the vessel and adapted to engage starting latch 5 of the torpedo, and 24 is a lever located within the torpedo boat and adapted to transmit motion to lever 4. 27 is a suitable connecting rod linking lever 24 with lever 25 which is located within the hull of the vessel and fulcrumed at 26'. As previously brought out, actuation of lever 25' which corresponds with lever 25 in Fig. 6, operates the starting latch of the torpedo, therefore when it is desired to launch the torpedo this said lever is operated. Now, if a torpedo of the standard pattern is employed the tripping of the starting latch, does not instantly unlock the gyroscope, it does, however, immediately admit motive fluid to a suitable engine 30, located within the torpedo for the propulsion of the same. This feature I preserve with the added improvement, however, of immediately or simultaneously unlocking the gyroscope 31. Gyroscope 31 which is preferably of the electrical type such as is described and claimed by me in my patent application No. 1127403 issued Feb. 9, 1915, for gyroscopically controlled torpedoes in which the gyroscope is started spinning previous to the launching period and consequently may be instantly unlocked whenever it is desired to release the torpedo without the usual delay of approximately one-half second which is common in the impulse variety of torpedo gyroscopes. To illustrate the carrying out of this feature of my invention I have added an extension 5' to the starting latch lever. 32 is a hook latch adapted to retain my gyroscope in a locked condition by holding pin 33 in engagement with the gyroscope in any suitable and well known manner against the pressure

of spring 34. (By referring to my above entitled patent the operation of this type of gyroscope as well as its general details of construction will be more clearly understood). Between lever 5' and hook 32 is a suitable connecting means 35 so that when the starting latch is tripped by the action of lever 25' hook 3 will be withdrawn thus freeing pin 33 which, owing to the action of 5 spring 34 will release the gyroscope from its locked condition. For convenience of illustration I have shown the switch lever 36 fulcrumed at 37 and adapted to complete an electric circuit, A, B, in which 38 is 10 a suitable source of electric current. By this arrangement it will be seen that the system may be operated as follows, *i.e.*: When approaching the firing zone lever 25' is moved to the left, this completes the 15 gyroscope motor circuit thus causing current to flow and causing the gyroscope to start spinning. Now when it is desired to release the torpedo, lever 25' is moved to the right which trips the starting latch of the weapon 20 thus starting the propelling engine and at the same time unlocking the gyroscope which is already spinning at full speed. In some instances it may be desirable to launch the 25 torpedo by other than manual means as for instance by an electromagnetic wave impulse sent out from a source other than within the vessel or it may be desirable to accomplish the operation quicker or with greater ease than may be possible manually and although various ways will suggest themselves 30 and various methods of operation will be immediately apparent to those versed in matters of this nature, I have for sake of illustration shown an electromagnetic launching mechanism of which 39 is an armature secured to 27. 40 and 40' are electromagnets, 41 is a suitable source of electrical energy and 42 is a switch lever adapted to 35 contact with 43 for the purpose of completing the electric circuits C, D and E. It will be understood that switch 42 may be operated manually, electrically or in any suitable and appropriate manner according to the 40 system under which my torpedo boat is being operated.

In Fig. 9 I illustrate conventionally a bow elevation of my vessel of slightly modified form and in which the torpedoes 3 and 3' are represented as farther apart than 45 in Fig. 3 with the consequence that greater space is allowed each side of the extension keel or center fin 1'. This permits the water to flow past the torpedoes with less resistance and consequently permits of 50 greater speed.

I do not, however, wish to limit myself to a specific construction of my vessel but illustrate this modification for the purpose of showing the great scope of designing possibilities. It will be noted that in both Figs. 55

1, 3 and 9 fin or keel 1' extends below the underside of my torpedoes. This is desirable as it affords a certain protection to the weapons, but is not, however, necessary.

In Fig. 10 which is an enlarged diagrammatic view of certain parts of Fig. 8, 4 is the external actuating lever previously described, 5 is the starting latch of the torpedo, 36 is the gyro spinning latch which is fulcrumed at 37. 37 is an integral extension of 36. 38' 70 is a contact point and 38 is a suitable source of current. 31 is a gyroscope. A and B represent the limbs of the electric circuit which is adapted to be closed by 37' when 36 is pushed to the right about the center 75 37 thus starting the gyroscope spinning when acted upon substantially as described by member 4.

From the above it will be seen that I provide an extremely simple and inexpensive 85 form of torpedo boat which is well adapted to certain military and naval uses and from which it is possible to accurately despatch a torpedo even though the vessel is rendered quite unstable due to the roughness of the 90 body of water in which it is operating.

The certainty with which a torpedo may be despatched from my vessel, as will be readily understood is due to the fact that at the instant that the torpedo is properly 95 directed upon the target, the gyroscope may be instantly unlocked thus insuring, irrespective of how the boat may be rolling in the water, that the course of the torpedo will lie in the right direction after it is 100 launched or released from the said torpedo vessel. It will be seen that the invention herein described provides a new and novel system of carrying and launching torpedoes and that the said invention provides an im- 105 portant improvement, therefore, in small torpedo boats in so far as it permits of the carrying of the torpedoes externally and also does not necessitate the employment of a torpedo tube. 110

Also it will be noted that the vessel may be made so small as to be conveniently carried by a larger vessel and that in operation irrespective of whether sent out from a vessel or from a shore station its function 115 will be to approach an enemy for the purpose of discharging a torpedo or torpedoes before the enemy can reduce or put it out of action by gun fire.

Also it will be noted that a wide choice of 120 systems of operation is possible owing to the unique construction of my vessel and furthermore it will be seen that the said vessel may either be handled manually from within the same, or as might be termed, 125 wirelessly from a distant station by any well known system of control.

Heretofore the practice has been to employ a torpedo gun or tube for launching torpedoes, and it will be noted that I have de- 130

panted from this practice and do not depend upon the tube or slideway, or other like device intended to hold the torpedo in a fixed direction during the launching period, but rather, I provide means for disengaging and quickly freeing the torpedo with the result that my construction is thereby greatly simplified.

The balance of my vessel is not upset when the torpedo is launched, and the speed of my vessel is not interfered with by the empty tube, also it is possible to build my vessel smaller and lighter, and I am not required to employ means for producing an ejecting impulse.

Having thus described an illustrative embodiment of my invention, I desire it to be understood that although specific terms are employed, they are used in a generic and descriptive sense and not for the purposes of limitation, the scope of the invention being set forth in the following claims:

1. In a torpedo boat a gyroscopically steered automobile torpedo detachably carried thereby, together with means for unlocking the gyroscope at the instant that the torpedo propelling means is started, the starting of the propelling means acting to detach the torpedo from the carrying means.

2. In a torpedo boat, a gyroscopically steered automobile torpedo, and means for simultaneously unlocking the gyroscope and starting the torpedo propelling means, the starting of the said propelling means causing the launching or releasing of the said torpedo.

3. In a torpedo boat, a gyroscopically steered automobile torpedo, carried thereby and adapted for initial spinning operation and means for simultaneously unlocking the gyroscope and starting the torpedo propelling means, the starting of said propelling means effecting the release or launching of the torpedo.

4. In a torpedo boat, a gyroscopically steered automobile torpedo, carried externally thereof and submerged and having means for initially spinning the gyroscope, and means within said boat for simultaneously unlocking the gyroscope and starting the torpedo propelling means, the starting of said propelling means acting to automatically release the said torpedo from said boat.

5. In a torpedo boat adapted to launch a gyroscopically steered automobile torpedo without a tube or gun, comprising detachable carrying means, means operable within the boat for initially spinning the torpedo gyroscope and for unlocking the gyroscope simultaneously with starting the torpedo propelling mechanism, and means operable within the boat for releasing the carrying

means, to permit the torpedo to fall away from the boat at the instant of launching.

6. In combination with a motor boat adapted for launching a gyroscopically steered torpedo, electrical means for initially spinning the torpedo gyroscope and starting the torpedo propelling mechanism, and placing the gyroscope in control of the steering mechanism, the release of the torpedo being effected by the operation of the propelling means.

7. In a dirigible vessel an automobile self steering torpedo adapted to be automatically launched, by the operation of the propelling mechanism, a gyroscope adapted to control the steering of the torpedo, and means operable from a remote station for unlocking the gyroscope simultaneously with the starting of the propelling means.

8. The combination with a boat, of a gyroscopically steered automobile torpedo suspended therefrom, and having means for spinning the gyroscope, means within the boat for operating the spinning means, and placing the gyroscope in control of the steering means, at the instant that the launching operation is initiated.

9. The combination with a motor boat, of a gyroscopically steered automobile torpedo detachably suspended thereunder, means within the boat for placing the gyroscope in operation and subsequently effecting the launching of the torpedo and unlocking the said gyroscope.

10. The method of launching gyroscopically steered torpedoes from motor boats which consists in initially spinning the gyroscope, and simultaneously placing the steering gear under gyroscopic control, and starting the propelling means for freeing the torpedo from the said boat.

11. The method of shooting automobile torpedoes which consists in spinning the gyroscope, placing the steering means under gyroscopic control, simultaneously with the starting of the propelling means, and utilizing the impulse from the propelling means to initially start the torpedo on its course.

12. The method of shooting automobile torpedoes which consists in spinning the gyroscopic fly wheel, pointing the torpedo with respect to the target and then simultaneously unlocking the gyroscope and starting the torpedo propelling engine for subsequently disengaging the torpedo.

13. The method of launching a self propelled torpedo which consists in spinning the gyroscope, pointing the torpedo with relation to a target, placing the steering means under control of the gyroscope while so pointed and utilizing the propelling power for the initial launching.

14. In a boat adapted to launch a gyroscopically steered automobile torpedo with-

out a tube or gun, operating means in said boat adapted upon actuation in one direction to cause the spinning of the torpedo gyroscope, and in the opposite direction to simultaneously start the torpedo propelling and steering means and effect the release of the torpedo from the boat.

15. In a torpedo boat adapted to launch a gyroscopically steered torpedo, magnetic means for starting the torpedo propelling means simultaneously with the unlocking of the gyroscope, the propelling means automatically effecting the release of the torpedo from the boat.

16. In a dirigible vessel, a submerged gyroscopically steered automobile torpedo hung only from means above its center of gravity and adapted to receive a launching impulse from its propelling means, means operable from a remote station for simultaneously unlocking the gyroscope, starting the propelling means, and detaching the torpedo from its hanging means.

17. The method of shooting a self propelled self steering torpedo, which consists in spinning the gyroscope, simultaneously unlocking same and starting the propelling means to effect the automatic release of the torpedo from the carrying means.

18. The combination with a boat, having a hull and keel of an automobile torpedo, de-

tachably secured to said hull at each side of the said keel, means for simultaneously actuating the torpedo propelling means and putting the gyroscopic steering means into operation, and effecting the automatic release of the torpedo.

19. The combination with a boat having a hull and keel, of an automobile torpedo secured to the hull at each side of the keel, means for detachably supporting the said torpedoes, and means operable within the boat for simultaneously starting the torpedo propelling mechanism, and the steering mechanism, and effecting the automatic release of the torpedo from the said attachments.

20. In combination with a boat, a gyroscopically steered automobile self launching torpedo suspended thereunder, means within the boat for placing the gyroscope in operation and subsequently effecting the launching of the torpedo simultaneously with the placing of the same under gyroscopic control.

In testimony whereof, I have affixed my signature, this 8th day of December, 1915, in the presence of two witnesses.

EDWARD F. CHANDLER.
